COTTON CLEANING CYLINDER

Orville Mitchell, Dallas, Tex.

Application January 6, 1936, Serial No. 57,787

13 Claims. (Cl. 19—94)

The general object of this invention is to provide a cotton cleaning cylinder which shall be characterized by extreme simplicity and lightness of construction while at the same time possessing great strength and rigidity and the working parts of which are readily detachable for purposes of repair and replacement.

Stated more in detail, an object of the invention is to provide a cleaning cylinder the drum whereof is formed of separable housing sections mounted on a frame, the abutting edges whereof provide angular projections which are secured together, and in detachably securing bladed strips to the drum by bolts, or the like, in such manner that the blades of the strip will be positioned at a distance from the angular projections on the rear side thereof relative to the direction of rotation of the cylinder.

Another object of the invention is to provide a cleaning cylinder, the drum whereof is formed of separable housing sections detachably mounted on a frame, the abutting edges whereof provide angular projections, and in detachably securing a bladed strip to each set of angular projections by bolts, or the like, which preferably at the same time secure the angular projections of the housing sections together.

Another object of the invention, in a drum constructed as above described, is to provide for detachably mounting blades on said drum by means of a number of independent metal strips extending longitudinally of the drum, and each of which is secured at one side to the drum and at its other side is provided with integral blades which are of greater height than the angular projections of the housing sections and extend at right angles to the length of the strip, so as to move edgewise relative to the direction of rotation of the cylinder.

Another object of the invention, in a drum constructed as above described, is to provide for detachably mounting blades on said drum by means of a number of independent metal strips extending longitudinally of the drum, and each of which is provided at one side with a flange adapted to be secured to the angular projections of the drum and at its other side with integral blades formed by bending up equally spaced sections of the edge portion of the strip at right angles to its base, or body, and which blades are of greater height than the angular projections of the housing sections and extend at right angles to the flange of the strip, so as to move edgewise relative to the direction of rotation of the cylinder.

Another object of the invention in a drum constructed as described, is to provide flanged strips provided with integral blades, the blades being located at one side of the strip and extending at right angles to, and being remote from, a flange provided at the other edge of the strip, and to detachably secure the flange of each strip to the angular projections of the drum in such manner that the flanges of the respective strips will precede the blades in the rotation of the cylinder.

Another object of the invention is to provide, as a separate article of manufacture, a bladed strip for use on the drums of cotton cleaning cylinders, said strip having a base portion curved to conform to the curvature of the periphery of the drum and being provided at one side with a longitudinal flange and at its other with upturned equally spaced sections forming blades, which blades are remote from and higher than the flange and extend at right angles to the latter.

In order that the advantages of my invention may be more clearly appreciated, it may be briefly explained that the cylinders commonly used in connection with cotton cleaning machinery comprise drums of some sort, having either vanes extending from one end of the drum to the other or rows of spikes secured to the periphery of the drum in staggered relation to each other.

Since it requires less power to force the separated spikes through heavy bodies of cotton, and because the spikes are more effective for loosening hulls and trash from the cotton, this type of drum is generally regarded as preferable to drums having longitudinal vanes, although the spiked form of drum is considerably more expensive to manufacture than the drum, or cleaning cylinder, provided with vanes.

My improved construction of cleaning cylinder embodies the strength of the vane construction of cylinder with the penetrating power of the spike construction, in that I provide the cylinder with blades mounted around and projecting from the periphery of the drum in a manner that causes the blades to move edgewise with the rotation of the cylinder against or through the stream or bodies of cotton being forced around the screen surface by the rotation of the cylinder. Thus such blades being flat and relatively wide are practically incapable of being bent in the direction of their extension, and moving edgewise, they can be more readily forced through the cotton than spikes, in that they present a thinner surface of metal to engage the

stream or bodies of cotton. They are therefore more effective than spikes for loosening hulls and trash from the bodies of cotton, besides having less tendency to sweep the cotton in a body around the surface of the screen.

Another disadvantage arising from the use of a drum equipped with spikes, and which is avoided by the use of my bladed construction of cylinder, is the fact that when the ends of the spikes engage the long locks of cotton containing a large number of seed, the trailing ends of the locks tend to whirl or twist, which results in the fibers between the seeds being spun more or less into threads, and the ends of the locks trailing back on each side of the spikes, being in contact with each other often rope or twist together; and such spinning or roping action results in the production of naps or threads by the action of the gin saws which lowers the grade or spinning value of the lint. With my improved cylinder, the ends of the blades which engage the cotton as it is being forced around the screen are not only of sufficient width to provide the necessary strength, but are wide enough to prevent the ends of large locks engaged by the front edge of the blades trailing back into contact with each other, which prevents the fibers being roped or twisted together, and which experience has shown results in marked improvement in ginning results, especially with the long-staple varieties of cotton.

By referring to the "width" of the blades, I intend to designate its linear extension in the direction of rotation of the cylinder; and this width may be of any desirable, or practicable extent, and will always be more than double the thickness of the blade.

The invention is illustrated in the accompanying drawings in which—

40 Figure 1 is a perspective view of a portion of one of my improved bladed strips;

Figure 2 is a cross-section through a cleaning cylinder constructed according to my invention;

45 Figure 3 is a longitudinal sectional view of one end portion of said cleaning cylinder taken on the line 3—3 of Fig. 2;

Figure 4 is a developed plan view of a portion of the cylinder on a reduced scale, illustrating the staggered relation of the blades; and

50 Figure 5 is a cross-sectional view of a portion of a cleaning cylinder illustrating a modification in the manner of securing the bladed strips to the drum of the cylinder.

Referring to Figure 1, the blades, 1, are formed 55 on a press with suitable dies from a strip of metal of a thickness to give the strength required, the base, 2, or wider portion of the strip, being curved transversely to conform to the curvature of the drum on which the strips are to be mounted.

60 The front edge of the strip is bent up at right angles to provide a flange, 3, to provide means for securing the strip to angular projections of the drum, the flange 3 being of less height than the blades 1. The blades 1 are bent at right angles to the base 2 at equal distances apart 65 along the rear edge portion of the strip, are provided with relatively wide flat outer ends and extend at right angles to the flange 3. The latter is provided at intervals throughout its length with bolt-holes, 3a.

70 The cleaning cylinder proper comprises a central shaft, 4, having a series of disks, 5, secured thereto, as by set-screws, 5a, the periphery of each disk having a flange, 6, as shown in Figure 3, to which the drum sections or housing

member, 7, are secured by bolts, 6a. Preferably four housing sections 7 are employed to form the shell of the drum, and each of these sections is provided at one side with an outwardly extended flange, 8, that are bolted together to 5 form a solid drum. The bolts, 8a, which secure the flanges, or angular projections 8 of the housing section 7 together, also extend through the bolt-holes 3a in the flanges 3 of the bladed strips, to secure the bladed strips to the angular projections in a manner such that each row of blades 1 will lie to the rear of the flanges 3 and angular projections 8, relative to the direction 10 of movement of the cylinder, and thus be pulled rather than pushed around with the rotation 15 of the cylinder. This is quite an important feature of the invention, since obviously if the cylinder were rotated in the opposite direction from that shown by the arrow in Figure 2, hard substances passing into the machine with the 20 cotton and engaged by the blades would tend to lift the bladed strip away from the drum and force the blades into the screen, thus destroying the screen and seriously damaging the cylinder. When, however, the cylinder is rotated in the 25 direction shown by the arrow, or with the blades trailing the angular projections of the drum to which the bladed strips are secured, any hard substances getting into the machine will merely force the base section of the strips tight against 30 the drum, there being no tendency for the blades to be lifted or forced out into contact with the screen.

In the modified construction, shown in Figure 5, the base 2 of the strip is not provided with 35 a flange but instead is connected to the periphery of the drum by bolts 7a, the rear edge of each strip simply abutting against the side of the angular projection or flange 8, adjacent which each bladed strip is secured.

40 When constructed as shown and described, neither the angular projections of the housing sections nor the front flange of the bladed strip of the preferred construction project far enough from the drum to act on the cotton, the action 45 being confined to the outer ends of the blade.

It will be apparent that if the blades formed in the trailing edges of the longitudinal strips did not project out from the drum a greater distance than the flange at the front of the strip, 50 or the angular projections on the drum to which said flange is secured, the blades would not be effective. That is to say, the action would be the same as with a vaned cylinder.

Aside from this bladed type of cylinder being 55 unusually effective in cleaning cotton and preparing it for the extracting mechanism by loosening hulls from entanglement with the cotton, it is extremely simple and inexpensive to construct. Also, it is stronger than the spiked type 60 of cylinder and has the further advantage of being equipped with quickly replaceable parts in case of damage.

With my invention, any one or all of the bladed strips can be quickly removed or replaced, where- 65 as with a spiked drum an entirely new cylinder must be substituted if the spikes become badly worn or damaged.

I claim:

1. A cotton cleaning cylinder comprising, in 70 combination, a shaft, a drum mounted thereon the periphery whereof is formed by a plurality of housing sections the abutting edges of which are provided with angular projections, and a series of strips secured to said projections and 75

having blades located at one side of and at a distance from the latter.

2. A cotton cleaning cylinder comprising, in combination, a shaft, a drum mounted thereon the periphery whereof is formed by a plurality of housing sections the abutting edges of which are provided with angular projections, and a series of strips secured to said projections and having spaced blades provided with flat outer ends extending at right angles to the length of the strips and located at one side of and at a distance from said projections.

3. A cotton cleaning cylinder comprising, in combination, a shaft, a drum mounted thereon the periphery whereof is formed by a plurality of housing sections the abutting edges of which are provided with connected angular projections, a series of strips extending longitudinally of the cylinder each of which has a flange extending along one side of said angular projections, and a series of separated blades extending along its other side, and means securing said angular projections and flange together.

4. A cotton cleaning cylinder comprising, in combination, a shaft, a drum mounted thereon the periphery whereof is formed by a plurality of housing sections the abutting edges of which are provided with connected angular projections, a series of independent strips, each of which has a flange extending along one side of said angular projections and separated blades remote from said flange, and means securing said angular projections and flange together.

5. A cotton cleaning cylinder comprising, in combination, a shaft, a drum mounted thereon the periphery whereof is formed by a plurality of housing sections the abutting edges of which are provided with angular projections, a series of strips each of which is provided throughout its length with separated blades extending at right angles to the length of the strip and with a flange remote from said blades and extending along one side of said angular projections, and means securing said angular projections and flange together.

6. A cotton cleaning cylinder comprising, in combination, a shaft, a cylindrical drum mounted thereon the periphery whereof is formed by a plurality of housing sections the abutting edges of which are provided with angular projections, and a series of longitudinal strips curved to conform to the curvature of the drum detachably secured at one side to said projections, and provided with blades at its other side.

55 7. A cotton cleaning cylinder comprising, in combination, a shaft, a closed cylindrical drum mounted thereon the periphery whereof is formed by a plurality of housing sections the abutting edges of which are provided with angular projections, and a series of strips secured to said projections, and having blades located at one side of and at a distance from the latter and of greater height than said angular projections.

65 8. A cotton cleaning cylinder comprising, in combination, a shaft, a closed cylindrical drum mounted thereon the periphery whereof is formed by a plurality of housing sections the abutting edges of which are provided with angular projections, and a series of bladed strips secured to said projections and supported on the periphery of the drum, and the blades of which are located at one side of and at a distance from said pro-

jections and are provided with flat outer ends positioned to move edgewise relative to the direction of the movement of the drum.

9. A cotton cleaning cylinder comprising, in combination, a shaft, a closed cylindrical drum mounted thereon the periphery whereof is formed by a plurality of circular housing sections the abutting edges of which are provided with angular projections, a series of metal strips each of which has one side bent outward to provide a flange and its other side provided at intervals with up-turned sections providing blades remote from and extending at right angles to said flange, and means for detachably securing the flanges of said strips to one side of the respective pairs of said angular projections in such manner as to cause said flanges to precede the blades in the direction of rotation of the cylinder.

10. A cotton cleaning cylinder comprising, in combination, a shaft, a drum mounted thereon the periphery whereof is formed by a plurality of housing sections the abutting edges of which are provided with angular projections, a series of longitudinal strips each of which has its forward edge portion, relative to the direction of rotation of the cylinder, bent outward to form a flange and its rear portion provided with separated bent-up sections providing blades extending at right angles to the length of the strip, and means for detachably securing said flanges to said respective angular projections.

11. A cotton cleaning cylinder comprising, in combination, a shaft, a drum mounted thereon the periphery whereof is formed by a plurality of housing sections the abutting edges of which are provided with angular projections, a series of strips each of which is provided throughout its length with separated blades extending at right angles to the length of the strip and with a longitudinal flange remote from said blades and extending along one side of said angular projections, and means securing said angular projections and flanges together with the blades of the respective strips having staggered relation to each other.

12. A cotton cleaning cylinder comprising, in combination, a shaft, a drum mounted thereon the periphery whereof is formed by a plurality of housing sections the abutting edges of which are provided with outward angular projections, and a series of longitudinal, bladed strips secured to the drum, the blades whereof have flat outer ends higher than said angular projections and extend at right angles thereto, said blades being located at one side of and at a distance from said projections.

13. A cotton cleaning cylinder comprising in combination a shaft, a drum mounted thereon, the periphery whereof is formed by a plurality of housing sections, the abutting edges of which are provided with angular projections, a series of strips each of which is provided with separated blades extending at right angles to the length of the strip and with a longitudinal flange in advance of the blades in the direction the cylinder rotates and extending along one side of said angular projections and means securing said angular projections and flanges together with the blades of the respective strips having staggered relation to each other.
